WASTE GAS INVENTOR
Joseph van Akkerveen,
By Charles Clark Laporte & Sons

UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed April 10, 1920. Serial No. 372,999.

To all whom it may concern:

Be it known that I, JOSEPH VAN ACKEREN, a citizen of the United States, residing in Pittsburgh, in the county of Allegheny and State of Pennsylvania, have invented a new and useful Improvement in Coking Retort Ovens, of which the following is a specification.

This invention comprehends improvements of especial utility in the coking retort oven art; and also comprehends certain improvements applicable to coking retort ovens of the well known Koppers cross-regenerative type exemplified in the patent to H. Koppers No. 818,033 dated April 17, 1906.

The invention has for one of its objects to incorporate in a coke oven a novel and highly efficient system of combustion in the flame or combustion flues of the heating walls, to the end that a constant flame or combustion is maintained in the flues of each heating wall, although the invention retains, with all of its advantages, the regenerative system of conserving the waste heat from the flues and of employing such waste heat for preheating the air that enters the flues to support combustion of the fuel burned therein. In other words, the invention combines the regenerative system, with its attendant periodic reversal of flow, in such a way with a flue system that flame is maintained constantly in all the flues of each heating wall, with the result that uniformity in temperature of the heating walls is promoted, thereby eliminating extreme temperature changes. The charges of coal within the several coking chambers are subjected constantly throughout their entire extent to the high temperatures of burning flames and no retardation of the carbonization process results from the reversal of flow through the regenerators. By the invention, the efficiency of a coking retort oven is greatly promoted, the carbonization process is carried on more evenly, with greater facility, and in a shorter time than has been heretofore possible, and temperature fluctuations throughout the system are greatly reduced.

The invention has for further objects such other improvements or advantages in construction and operation as are found to

obtain in the structures and devices hereinafter described or claimed.

In the accompanying drawings, forming a part of this specification, and showing, for purposes of exemplification a preferred form and manner in which the invention may be embodied and practiced, but without limiting the claimed invention specifically to such illustrative instance or instances:

Fig. 1 is a composite vertical sectional elevation through a coking retort oven of a type embodying features above specified and equipped with the improvements of the present invention;

Fig. 2 is a composite vertical sectional elevation taken longitudinally of the coke oven battery;

Fig. 6 is a fragmentary detailed horizontal sectional view of a heating wall taken on the several planes indicated by the line 6—6 of Fig. 1;

Fig. 7 is a vertical section through the upper portion of a heating wall taken in a plane indicated by the line 7—7 of Fig. 6.

Fig. 8 is an enlarged perspective view, broken away in different vertical and horizontal planes, to illustrate more clearly the flue construction and other parts of a heating wall;

Fig. 9 is a partial top plan view of the coking retort oven;

Fig. 10 is a detailed fragmentary vertical section of the upper portion of the retort oven taken longitudinally of the battery; and

Fig. 11 is a plan view illustrating the flow through the flues, channels and tops of the regenerators.

The same characters of reference indicate the same parts throughout the several views.

In its present embodiment, the invention is incorporated in a coking retort oven or

coke oven battery having features of the well known Koppers cross-regenerative type exemplified in the patent to H. Koppers hereinabove mentioned, which retort oven or battery includes in its construction crosswise extending parallel heating walls constituted of series of vertical flame or combustion flues, elongated coking chambers or ovens intermediate the heating walls and parallel therewith, and crosswise extending regenerators located at a lower level than the coking chambers and the heating walls and parallel therewith. For convenience, the present description will be confined to this use of the invention; features of construction are, however, readily susceptible of other valuable applications, and consequently, it is manifest that the scope of the invention is by no means confined to the specific use and specific embodiment herein described as an illustrative example.

Referring to the drawings, there are illustrated sectional views of a coke oven battery of the by-product type, such as has been hereinbefore mentioned, which embodies in its construction a plurality of crosswise elongated heating walls 11 and a plurality of intermediate crosswise elongated vertical coking chambers or ovens 12, 12. The heating walls 11 form the side walls of the respective coking chambers 12, as shown more particularly in Fig. 2, and in the present instance are supported by the heavy supporting or pillar walls 13, 13 extending crosswise of the battery and located, as shown, beneath the respective heating walls 11. These pillar walls collectively form the main support for the entire superstructure of the oven battery and are themselves firmly supported upon a flat mat or platform which constitutes the sub-foundation on which the entire battery rests. The coal to be coked is charged into the several coking chambers or ovens 12 through charging holes 14 located in the top 15 of the oven battery and positioned directly above the ovens or chambers 12, as shown in Fig. 1. These charging holes 14 are equipped with the usual removable covers, not shown, which are removed when charging any of the several ovens and placed in position to close the tops of the ovens during the entire coking operation.

Heat for coking the charges of coal in the several ovens or chambers 12 is derived from the heating walls 11, which, as before mentioned, extend crosswise of the battery at the sides of the coking chambers. Both the construction and the functioning of these heating walls constitute important features of the present invention. Referring now more particularly to Fig. 3, each heating wall 11 is constituted of two series, 15 and 16, of substantially triangular flame or combustion flues alternately facing oppositely toward

the coking chambers contiguous to either side of each such heating wall. Each of such flues, by reason of its triangular form, is relatively narrow transversely of the wall and presents a wide heating face toward the contiguous coking chamber. Disposed along the longitudinal center of each heating wall 11 and located between the aforesaid two series of vertical flues 15 and 16 is a series of vertical channels 17, respectively staggered with relation to the flues on the opposite sides of them, and operable alternately as air inlet or waste gas exhaust channels. In the present embodiment of the invention, alternate channels 17 operate as air inlet channels, while the channels intermediate such alternate channels are concurrently operated as waste gas exhaust channels.

The crosswise regenerators 18 of the retort oven or battery are located at a lower level than the aforesaid heating walls 11 and coking chambers 12 and in the present instance extend in parallelism beneath the coking chambers 12 between the pillar walls 13. Each regenerator 18 is a chamber containing open brick work, commonly called checker-work, and indicated at 19, with distributing sole channels 20 underneath such checker-work, the channels forming the soles of such chambers and opening up into the checker-work; these regenerators in alternation are heated by the hot combustion products that draw off from the flame or combustion flues hereinbefore mentioned and then impart such heat to the air that they feed into these flame flues. The checkerwork 19 of each regenerator is divided by a vertical partition 21 which extends longitudinally of the regenerator and separates the checkerwork into two compartments located on the opposite sides of such partition.

In accordance with the invention, there is located in the top of each regenerator and at the top of the aforesaid vertical partition 21 a horizontal partition 22 formed by a plurality of bricks 23, as shown more particularly in Figs. 4 and 5. This horizontal partition 22 provides a channel 24 that extends longitudinally in the top of each crosswise regenerator and, as shown in Fig. 4, each such channel 24 is subdivided into compartments 25 by means of transverse vertical partitions 26 connecting the pillar walls on the opposite sides of a regenerator compartment. The bricks 23 that form the bottoms of the respective compartments 25 of the aforesaid channel 24 are formed with ports 27 and these ports 27 are so arranged in the channel 24 that alternate compartments 25 thereof communicate through their ports 27 with the checkerwork on one side of the vertical partition 21 and the alternate compartments 25 intermediate such alternate compartments aforesaid communicate with the checkerwork on the opposite side

of the vertical partition 21. Leading from each alternate channel compartment 25 are two ducts 28 and 29 that respectively enter the bottoms of two adjacent flame or combustion flues of a series 16 of a heating wall 11 on one side of the aforesaid channel 24; and also leading from the same alternate compartments 25 are another pair of ducts 28 and 29 respectively entering the bottom of two adjacent flame flues 15 of the heating wall 11 on the opposite side of said longitudinal channel 24. The compartments 25 intermediate the compartments aforesaid are each connected by two oppositely extending ducts 30 with alternate channels 17 of the two heating walls on the opposite sides of said regenerator channel 24. With this construction and by reason of the compartmental channel and the arrangement of ducts just described, one side of each regenerator checkerwork, communicates with all the flame flues of the two series 15 and 16 respectively contiguous to such regenerator and located in the contiguous heating walls 11 on the opposite sides thereof; whereas the other side of each regenerator checkerwork is in communication with alternate channels 17 of the two series of such channels in the two contiguous heating walls located on the opposite sides of the regenerator. The channels 17 intermediate such alternate channels of the heating wall, on the right side of a regenerator for example, are in communication with one side of the next adjacent regenerator to the right; and the intermediate channels 17 of the series in the heating wall on the left side of such first regenerator are in communication with one side of the next adjacent regenerator to the left. The remote series of flame flues of the right and left heating walls contiguous to each regenerator are respectively in communication with the adjacent regenerators on the right and left of the regenerator which feeds, or is fed by the contiguous series of flame flues of both such heating walls. Extending crosswise of the battery in each pillar wall 13 and located beneath the heating wall 11 thereabove, is a pair of gas channels 31 and 32. These channels 31 and 32 communicate respectively by means of a series of ducts 33 and 34 with the bottoms of the individual flame flues 15 and 16 of the two series of flame flues in a heating wall above a pair of gas channels 31 and 32.

Referring more particularly to Figs. 8 and 10, each heating wall 11 is provided with a plurality of chambers 35, which chambers are located above the upper ends of the series of flues 15 and 16 and respectively connect a flue of one series 15 with a directly opposite flue of the other series 16. Fitted within the top of each flue of both series 15 and 16 is a plug 36 having a port 37

through which the flue communicates with the aforesaid chamber 35. Each plug 36 is furthermore provided with a tapering depending cylindrical portion 38 the outer face of which is spaced from the tapering 70 and concentric port 39 at the top of the flue to provide a surrounding passageway 40, the purpose of which will be presently described. A pair of access flues 41 and 42 extend from the top 15 of the battery to the 75 opposite ends of each aforesaid chamber 35, these access flues affording a means of communication from the top of the oven with the interior of the chamber 35. Normally such access flues are closed by suitable cover 80 plates. Between each pair of access flues 41, 42 is a vertical gas-supply duct 43 formed in a single gun brick let in from the top 15 of the battery. The duct 43 terminates at its lower end in a flaring nozzle 85 44 through which fuel gas may flow into either one of the flues 15 or 16 that communicate with the chamber 35 above them. As shown in Fig. 8 the flaring nozzle 44 is located at the upper end of the chamber 35 90 and between the two flues 15 and 16, and, because of the coincidence of the greatest cross-sectional area of the nozzle with the discharge end thereof, and the inclined walls that extend downwardly in opposite 95 directions toward the respective flues 15 and 16, the gas may pass with facility into either one of said flues. The series of gas-supply ducts 43 in the top of a heating wall are supplied from a gas main 45 suitably supported over the top of each heating wall, as shown in Figs. 9 and 10, and provided with a series of gas guns 46 which enter the inlets of the aforesaid ducts 43.

Near the upper ends of all the channels 105 17 are plugs 17^a, which control the flow of air or exhaust out of or into said channels.

The upper end of each alternate channel 17 of the series of such channels in each heating wall is provided with a pair of 110 horizontally extending branching by-passes 47, see Figs. 6, 7, and 8, which branching by-passes 47 respectively lead to the surrounding passages 40 of a pair of adjacent flues 16 of the same series on one side of the 115 heating wall, it being understood that all of the flues of this series are connected in pairs, by similar by-passes 47 with the alternate channels 17. The channels 17 intermediate such alternate channels aforesaid 120 are each connected, by means of similar by-passes 48 with a pair of adjacent flues 15 of the other series on the opposite side of the heating wall, the flues of the series 15 being so connected in pairs with the alternate channels 17 intermediate the alternate channels that are connected by the by-passes 47 with pairs of flues of the series 16 above set forth.

With the above described construction, 125

constant flame or combustion is maintained in all of the flame or combustion flues of each heating wall, irrespective of whether the flow is up or down in a series of such flues. According to the present embodiment of the invention, when a series of flues 15, for example, of a heating wall is being fed with gas from the bottom by means of a gas channel 31 or 32, the opposite series of flues 16 in the same heating wall is concurrently being fed with gas from the top by means of the top supply main 45. In this manner, up-burning flame is maintained in all the flues of a series on one side of the heating wall, while simultaneously a down-burning flame is maintained in all the flues of the other series on the opposite side of the heating wall. Hence, throughout the battery combustion is maintained in all of the flues, notwithstanding reversal of flow through the regenerators and in the flues, the manner of which will be hereinafter explained, with the result that both sides of each heating wall are being constantly heated by constantly burning flames, temperature conditions are equalized throughout the battery or plant as a whole, and the coking process proceeds uniformly without interruption from end to end of each coking chamber. The combined up-flame and down-flame in each heating wall results in a considerable extension of the capacity of the wall to maintain coking temperature in a vertical direction, thereby permitting an increase in the height of the heating walls, with a consequent increase in the height of the coking chambers and their individual coking capacity.

In order to illustrate advantages and novel features of the invention and in exposition of the above general statements of operation and results, the following detailed description of operation of a coking retort oven, constructed in the manner above described and illustrated in the accompanying drawings is now given.

The several regenerators 18 each extend crosswise of the battery from each side thereof, and reversal of flow through such regenerators takes place, at the end of such periodic intervals as may be determined by practice longitudinally of the battery and in alternate regenerators, instead of from side to side of the battery, as has been heretofore the more common practice in coking retort ovens of the Koppers cross-regenerative type. For example, an alternate series of regenerators reckoned longitudinally of the battery are operated as inflow chambers, while concurrently the series of intermediate alternate regenerators reckoned in the same manner, are operated as outflow chambers. Starting with an inflow-operating regenerator, the air from the sole channels 20 enters the checker-

work on the opposite sides of the partition 21, such air being divided into two courses of flow by the partition 21. From the checkerwork on one side of the partition 21, the air flows into alternate chambers 25 of the channel 24 in the top of the regenerator, and thence flows from each of such alternate chambers through two pairs of ducts 28 and 29 into two pairs of flues 15 and 16 of the two series of contiguous flues in the heating walls 11 respectively located on opposite sides of the aforesaid regenerator. On the other hand, the air from the checkerwork on the opposite side of the central partition 21 of the regenerator passes into the chambers 25 intermediate the alternate chambers aforesaid, and from each one of such chambers 25 flows through two ducts 30 into alternate channels 17 of the series of such channels in each one of the two contiguous heating walls 11 on the opposite sides of the aforesaid regenerator. It will be here noted that all the flues of the two series 15 and 16 that are directly contiguous to the opposite faces of the heating walls forming the sides of the coking chamber above the regenerator, are supplied with air. Gas is turned on, by means of the usual gas controlling connections, into the gas channels 31 and 32 beneath such series of flues 15 and 16, and entering such flues through the ducts 33 and 34 ignites in the atmosphere of highly pre-heated air supplied from one side of the regenerator. The exhaust or waste gases from the contiguous series of flues 15 and 16 in the two heating walls on the opposite sides of a regenerator pass into the ports 39 at the tops of the flues of the two series. In such ports 39, the waste gas divides into two courses: a portion of the waste gas enters the surrounding passages 40 in the ports 39 and from these surrounding passages, flows through by-passes 48 into the alternate channels 17 of the two heating walls aforesaid. Flowing down the alternate channels 17 of the two heating walls the exhaust gas in the heating wall on the right side of the inflow operating regenerator finally reaches the outflow operating regenerator through the ducts 30 hereinbefore described and from such regenerator flows into the usual waste gas main. The waste gas in the alternate channels 17 of the heating wall on the left side of the inflow operating regenerator pursues a similar course through the outflow operating regenerator on the left of the inflow operating regenerator, (see Fig. 11).

The other portion of the waste gas from the ports 39 of the series of upburning flues 15 and 16 passes through the ports 37 of the plugs 36 into the chambers 35 that connect such upburning flues with the down-burning flues on the remote side of the

respective heating walls 11. A constant flow of gas is maintained in the gas supply ducts 43 above the respective chambers 35 and the gas flows from such ducts through the flaring nozzles 44 into the ports 37 of the plugs in the series of flues on the remote side of the aforesaid upburning flues. That is to say, the gas flows into the downburning flues 16 of the right hand heating wall 10 of which the flues 15 are the upburning flues and the gas from the ducts 43 flows into the flues 15 of the left hand heating wall of which the flues 16 are the upburning flues. As the gas enters the two remote 15 series of downburning flues 16 and 15 of the two heating walls it mingles with waste gas that issues from the ports 37 of the two contiguous series of upburning flues. The waste gas serves to dilute the fuel gas and 20 consequently acts to lengthen the flame in the downburning flues, thereby increasing the volume of flame of such downburning flues and consequently increasing the flame heated area of the heating walls. This permits the making of very high heating walls, while preserving substantially uniform temperature conditions throughout a substantial extent of such walls. The lengthening of 25 the flame in the downburning flues, moreover, prevents an intense flame concentration in the upper extremities of the heating flues where it is most desirable to keep the temperature relatively low, in order to avoid destruction of the gases of distillation which 30 arise from the charge of coal in the intermediate coking chambers.

The air for supporting combustion in the downburning flues 16 and 15 is derived from the surrounding passages 40 in the ports 39 40 at the top of such flues. As before mentioned, alternate channels 17 of the series of channels in the heating walls on the opposite side of an inflow operating regenerator are supplied with preheated air from such regenerator. The air flows upward in such channels 17 and branching through the by-passes 47 enters the aforesaid surrounding 45 passages 40 in the ports of the downburning flues. Each air supply channel 17 supplies 50 two adjacent downburning flues by means of its branching by-passes 47.

The exhaust from the right and left hand series of downburning flues 16 and 15 passes through the ducts 28 and 29 into the regenerators respectively located on the right and the left of the inflow operating regenerator and flowing through the checkerwork on one side of the central partition 21 of each of such regenerators passes into the sole channels and thence into the usual waste gas main.

On reversal of the oven at the end of an operating period determined by practice, and by means of any preferred type of reversing mechanism, the regenerators that

prior to the reversal operated as inflow regenerators are each switched to outflow regenerators, and the outflow operating regenerators become inflow operating regenerators; the upburning series of flues switch 70 functions with the downburning series of flues; and the lower supply of gas is turned off from the previously upburning flues and turned on into the mains of the previously downburning flues. No reversal connections 75 are necessary for switching the supply of gas fed through the upper gas ducts 43 from one series of flues of the heating wall to the other. By reason of the position of the nozzles at the lower ends of the ducts 43, the gas 80 may be readily directed into one set of flues or the other by the draft from the upburning flues. It should be also noted that at the period of reversal air channels 17 become exhaust channels and exhaust channels 17 become air channels.

The flow through the ports 37 at the top of the individual flues may be regulated by slide bricks 48 positioned at the bottoms of the chambers 35 and within convenient reach 85 of an operator through the inspection holes 41 and 42. In the top of the oven are another series of access flues 47, adapted to be closed by the usual covers and respectively extending from the top face of the oven to 90 the tops of the several channels 17. These access flues permit access to the regulation nozzles 50 in the upper part of the channels 17.

The divided checkerwork in the several regenerators and the compartmental channel construction in the top of such regenerators permits a flow from each regenerator to the communicating channels 17 that is separate 100 from the flow from the same regenerator to the communicating flues 15 and 16. This construction permits separate regulation of the flow to and from the flues and the channels, as it is obviously necessary to control the flow to and from the channels somewhat differently from the flow to and from the flues. The channels, it should be noted, when operating as air channels, feed the downburning flues and the air must flow to 105 nearly the top of the oven before it enters such downburning flues; whereas the air from the other side of the regenerators passes substantially directly into the upburning flues.

In the operation of the oven or battery, both sides of a coking chamber are heated either by upburning or downburning flues, there being in the present instance, the same direction of flow in the series of flues on both sides of a coking chamber. For example, if 110 a pair of contiguous flues on the opposite sides of a coking chamber are operating as upburning flues, the pair of contiguous flues of the next adjacent coking chamber are operated as downburning flues. The reversal 115 120 125 130

takes place between alternate pairs of series of contiguous flues throughout the oven battery.

The invention as hereinabove set forth is embodied in a particular form of construction but may be variously embodied within the scope of the claims hereinafter made.

I claim:

1. In a coking retort oven, in combination: a plurality of coking chambers; heating walls contiguous to said coking chambers and respectively constituted of two series of substantially triangular combustion flues arranged on opposite sides of the heating walls, and a series of channels intermediate such flue-series operable alternately as air or exhaust passages; gas-supply ducts at the top of each heating wall and respectively communicating with two flues, one of each series; individual gas-supply ducts at the bottom of each heating wall and respectively communicating with the individual flues of each series; regenerators located at a lower level than the coking chambers and the heating walls, the flow through alternate regenerators being concurrently in the same direction, while the flow through the other regenerators is concurrently in the opposite direction, said regenerators respectively embodying, checker-work divided by a partition extending longitudinally of the regenerator and a channel above such checker-work sub-divided into two groups of compartments, one group comprising alternate compartments communicating with the checker-work on one side of said longitudinal partition and communicating by ducts with the contiguous flues of the heating walls on the opposite sides of said regenerator, and the other group comprising the intermediate compartments communicating with the checker-work on the other side of said longitudinal partition and communicating by ducts with alternate air or exhaust channels of such heating walls; and means for admitting fuel gas to the bottom gas-supply ducts of the flues contiguous to the inflow operating regenerators and for concurrently shutting off the supply of fuel gas from the gas-supply ducts of the flues contiguous to the outflow operating regenerators; substantially as specified.

2. In a coking retort oven, in combination: a plurality of coking chambers; heating walls contiguous to said coking chambers and respectively constituted of two series of combustion flues arranged on opposite sides of the heating walls, and a series of channels intermediate such flue-series operable alternately as air or exhaust passages; gas-supply ducts at the top of each heating wall and respectively communicating with two flues, one of each series; individual gas-supply ducts at the bottom of each heating wall and respectively communicating with

the individual flues of each series; regenerators located at a lower level than the coking chambers and the heating walls, the flow through alternate regenerators being concurrently in the same direction, while the flow through the other regenerators is concurrently in the opposite direction, said regenerators respectively embodying, checker-work divided by a partition extending longitudinally of the regenerator and a channel above such checker-work sub-divided into two groups of compartments, one group comprising alternate compartments communicating with the checker-work on one side of said longitudinal partition and communicating by ducts with the contiguous flues of the heating walls on the opposite sides of said regenerator, and the other group comprising the intermediate compartments communicating with the checker-work on the other side of said longitudinal partition and communicating by ducts with alternate air or exhaust channels of such heating walls; and means for admitting fuel gas to the bottom gas-supply ducts of the flues contiguous to the inflow operating regenerators and for concurrently shutting off the supply of fuel gas from the gas-supply ducts of the flues contiguous to the outflow operating regenerators; substantially as specified.

3. In a coking retort oven, in combination: a plurality of coking chambers; heating walls contiguous to said coking chambers and respectively constituted of two series of substantially triangular combustion flues arranged on opposite sides of the heating walls, and a series of channels intermediate such flue-series operable alternately as air or exhaust passages; continuous supply gas-ducts at the top of each heating wall and respectively communicating with two flues, one of each series; individual gas-supply ducts at the bottom of each heating wall and respectively communicating with the individual flues of each series; regenerators located at a lower level than the coking chambers and the heating walls, the flow through alternate regenerators being concurrently in the same direction, while the flow through the other regenerators is concurrently in the opposite direction, said regenerators respectively embodying, checker-work divided by a partition extending longitudinally of the regenerator and a channel above such checker-work sub-divided into two groups of compartments, one group comprising alternate compartments communicating with the checker-work on one side of said longitudinal partition and communicating by ducts with the contiguous flues of the heating walls on the opposite sides of said regenerator, and the other group comprising the intermediate compartments communicating with the checker-work on the other side of said longitudinal partition and

communicating by ducts with alternate air or exhaust channels of such heating walls; and means for admitting fuel gas to the bottom gas-supply ducts of the flues contiguous to the inflow operating regenerators and for concurrently shutting off the supply of fuel gas from the gas-supply ducts of the flues contiguous to the outflow operating regenerators; substantially as specified.

4. In a coking retort oven, in combination: a plurality of coking chambers; heating walls contiguous to said coking chambers and respectively constituted of two series of combustion flues arranged on opposite sides of the heating walls, and a series of channels intermediate such flue-series operable alternately as air or exhaust passages; continuous supply gas-ducts at the top of each heating wall and respectively communicating with two flues, one of each series; individual gas-supply ducts at the bottom of each heating wall and respectively communicating with the individual flues of each series; regenerators located at a lower level than the coking chambers and the heating walls, the flow through alternate regenerators being concurrently in the same direction, while the flow through the other regenerators is concurrently in the opposite direction, said regenerators respectively embodying, checkerwork divided by a partition wall extending longitudinally of the regenerator and a channel above such checkerwork subdivided into two groups of compartments, one group comprising alternate compartments communicating with the checkerwork on one side of said longitudinal partition and communicating by ducts with the contiguous flues of the heating walls on the opposite sides of said regenerator, and the other group comprising the intermediate compartments communicating with the checkerwork on the other side of said longitudinal partition and communicating by ducts with alternate air or exhaust channels of such heating walls; and means for admitting fuel gas to the bottom gas-supply ducts of the flues contiguous to the inflow operating regenerators and for concurrently shutting off the supply of fuel gas from the gas-supply ducts of the flues contiguous to the outflow operating regenerators; substantially as specified.

5. In a coking retort oven, in combination: a plurality of coking chambers; heating walls contiguous to said coking chambers and respectively constituted of two series of combustion flues arranged on opposite sides of the heating walls, and a series of channels intermediate such flue-series operable alternately as air or exhaust passages; gas-supply ducts at the top of each heating wall and respectively communicating with two flues, one of each series; individual gas-supply ducts at the bottom of each heating wall and respectively communicating with the individual flues of each series; regenerators located at a lower level than the coking chambers and the heating walls, said regenerators respectively embodying, checkerwork divided by a partition wall extending longitudinally of the regenerator and a channel above such checkerwork sub-divided into compartments, the checkerwork on each side of such longitudinal partition wall communicating with alternate compartments, alternate compartments of the channel communicating by ducts with the contiguous flues of the heating walls on the opposite sides of said regenerator and the compartments intermediate such alternate compartments communicating by ducts with alternate air or exhaust channels of such heating walls; means for reversing the direction of flow through alternate regenerators in series longitudinally with respect to the coking retort oven; and means for admitting fuel gas to the bottom gas-supply ducts of the flues contiguous to the inflow operating regenerators and for concurrently shutting off the supply of fuel gas from the gas-supply ducts of the flues contiguous to the outflow operating regenerators; substantially as specified.

6. In a coking retort oven, in combination: a plurality of coking chambers; heating walls contiguous to said coking chambers and respectively constituted of two series of combustion flues arranged on opposite sides of the heating walls, and a series of channels intermediate such flue-series operable alternately as air or exhaust passages; gas-supply ducts at the top of each heating wall and respectively communicating with two flues, one of each series; individual gas-supply ducts at the bottom of each heating wall and respectively communicating with the individual flues of each series; regenerators located at a lower level than the coking chambers and the heating walls, said regenerators respectively embodying, checkerwork divided by a partition wall extending longitudinally of the regenerator and a channel above such checkerwork sub-divided into compartments, the checkerwork on each side of such longitudinal partition wall communicating with alternate compartments, alternate compartments of the channel communicating by ducts with the contiguous flues of the heating walls on the opposite sides of said regenerator and the compartments intermediate such alternate compartments communicating by ducts with alternate air or exhaust channels of such heating walls; means for permitting individual control of the flow through the checkerwork on the opposite sides of such longitudinal partition wall; means for reversing the direction of flow through alternate regenerators in series; and means for admitting fuel gas

to the bottom gas-supply ducts of the flues contiguous to the inflow operating regenerators and for concurrently shutting off the supply of fuel gas from the gas-supply ducts of the flues contiguous to the outflow operating regenerators; substantially as specified.

7. In a coking retort oven, in combination: a plurality of coking chambers; heating walls intermediate such coking chambers and constituted of two series of substantially triangular combustion flues and of a series of channels intermediate such flue-series; and cross-regenerators disposed at a lower level than the coking chambers and heating walls, such regenerators being sub-divided into compartments, with a compartment of each regenerator directly communicating with combustion flues and another compartment thereof directly communicating with intermediate channels of the heating walls; substantially as specified.

8. In a coking retort oven, in combination: a plurality of coking chambers; heating walls intermediate such coking chambers and constituted of two series of combustion flues and of a series of channels intermediate such flue-series; and cross-regenerators disposed at a lower level than the coking chambers and heating walls, such regenerators being sub-divided into compartments, with a compartment of each regenerator directly communicating with combustion flues and another compartment thereof directly communicating with intermediate channels of the heating walls; substantially as specified.

9. In a coking retort oven, in combination: a plurality of coking chambers; heating walls intermediate such coking chambers and constituted of two series of combustion flues and of a series of channels intermediate such flue-series; cross-regenerators disposed at a lower level than the coking chambers and heating walls, such regenerators being sub-divided into compartments with a compartment of each regenerator directly communicating with combustion flues and another compartment thereof directly communicating with intermediate channels of the heating walls; and means for reversing the direction of flow through such regenerators; substantially as specified.

10. In a coking retort oven, in combination: a plurality of coking chambers; heating walls intermediate such coking chambers and constituted of two series of combustion flues and of a series of channels intermediate such flue-series; cross-regenerators disposed at a lower level than the coking chambers and heating walls, such regenerators being sub-divided into compartments with a compartment of each regenerator directly communicating with combustion flues and another compartment thereof

directly communicating with intermediate channels of the heating walls; and means for reversing the direction of flow through alternate regenerators in series longitudinally with respect to the coking retort oven; substantially as specified.

11. In a coking retort oven, in combination: a plurality of coking chambers; heating walls intermediate such coking chambers and constituted of two series of combustion flues and of a series of channels intermediate such flue-series; cross-regenerators disposed at a lower level than the coking chambers and heating walls, such regenerators being sub-divided into compartments with a compartment of each regenerator directly communicating with combustion flues and another compartment thereof communicating with intermediate channels of the heating walls; and means for permitting separate control of the flow in each compartment of the regenerators; substantially as specified.

12. In a coking retort oven, in combination: a plurality of coking chambers; heating walls intermediate such coking chambers and constituted of two series of combustion flues and of a series of channels intermediate such flue-series; and cross-regenerators disposed at a lower level than the coking chambers and heating walls, such regenerators being subdivided into compartments, with a compartment of each regenerator directly communicating with all the combustion flues contiguous to such regenerator and another compartment thereof directly communicating with alternate channels of the heating walls containing such contiguous series of combustion flues; substantially as specified.

13. In a coking retort oven, in combination: a plurality of coking chambers; heating walls intermediate such coking chambers and constituted of two series of vertical combustion flues alternately operable as upburning and as downburning flues and of a series of channels alternate units of which operate as exhaust channels while the intermediate units operate as air channels; means for feeding fuel gas to the flues while the flow is in either direction; means for periodically reversing the direction of flow in the flues and channels; and a periodically-reversible regenerative system for receiving the exhaust from all the flues and exhaust channels, combined with supply connections for conveying pre-heated air from such system to the upflow flues and air channels; substantially as specified.

14. In a coking retort oven, in combination: a plurality of coking chambers; heating walls intermediate such coking chambers and constituted of two series of vertical combustion flues alternately operable as upburning and as downburning flues and

- of a series of channels alternate units of which operate for upflow while the intermediate units operate for downflow; means for feeding fuel gas to the flues when the flow is in either direction; means for periodically reversing the direction of flow in the flues and channels; and a periodically-reversible regenerative system for receiving the exhaust from all the flues and downflow channels, combined with supply connections for conveying preheated air from such system to all the upflow flues and upflow channels; substantially as specified.
15. In a coking retort oven, in combination: a plurality of coking chambers; heating walls intermediate such coking chambers and constituted of two series of vertical combustion flues alternately operable as upburning and as downburning flues, one series of flues operating as upburning flues while the other series is operating as downburning flues, and of a series of channels alternate units of which operate for upflow while the intermediate units operate for downflow; means for feeding fuel gas to the flues when the flow is in either direction; means for periodically reversing the direction of flow in the flues and channels; and a periodically-reversible regenerative system for receiving the exhaust from all the flues and downflow channels, combined with supply connections for conveying preheated air from such system to all the upflow flues and upflow channels; substantially as specified.
16. In a coking retort oven, in combination: a plurality of coking chambers; heating walls intermediate such coking chambers and constituted of two series of vertical combustion flues alternately operable as upburning and as downburning flues and of a series of channels alternate units of which operate as exhaust channels while the intermediate units operate as air channels; supply connections for permitting exhaust to pass from the upburning to the downburning flues; means for feeding fuel gas to the flues when the flow is in either direction; means for periodically reversing the direction of flow in the flues and channels; and a periodically reversible regenerative system for receiving the exhaust from all the flues and exhaust channels, combined with supply connections for conveying preheated air from such system to all the upflow flues and air channels; substantially as specified.
17. In a coking retort oven, in combination: a plurality of coking chambers; heating walls intermediate such coking chambers and constituted of two series of vertical combustion flues alternately operable as upburning and as downburning flues and of a series of channels alternate units of which operate as exhaust channels for the upburning flues while the intermediate units operate as air channels for supplying preheated air to the downburning flues; means for feeding fuel gas to the flues when the flow is in either direction; means for periodically reversing the direction of flow in the flues and channels; and a periodically-reversible regenerative system for receiving the exhaust from all the flues and exhaust channels, combined with supply connections for conveying preheated air from such system to all the upflow flues and air channels; substantially as specified.
18. In a coking retort oven, in combination: a plurality of coking chambers; heating walls intermediate such coking chambers and constituted of two series of vertical combustion flues alternately operable as upburning and as downburning flues and of a series of channels alternate units of which operate as exhaust channels for the upburning flues while the intermediate units operate as air channels for supplying preheated air to the downburning flues, means for feeding fuel gas to the flues when the flow is in either direction; means for supplying a neutral gaseous diluent to the downburning flues; means for periodically reversing the direction of flow in the flues and channels; and a periodically reversible regenerative system for receiving the exhaust from all the flues and exhaust channels, combined with supply connections for conveying preheated air from such system to all the upflow flues and air channels; substantially as specified.
19. In a coking retort oven, in combination: a plurality of coking chambers; heating walls intermediate such coking chambers and constituted of two series of vertical combustion flues alternately operable as upburning and as downburning flues and of a series of channels alternate units of which operate as exhaust channels for the upburning flues while the intermediate units operate as air channels for supplying preheated air to the downburning flues; means for feeding fuel gas to the flues when the flow is in either direction; means for permitting waste gas to flow into the downburning flues; means for periodically reversing the direction of flow in the flues and channels; and a periodically-reversible regenerative system for receiving the exhaust from all the flues and exhaust channels, combined with supply connections for conveying preheated air from such system to all the upflow flues and air channels; substantially as specified.
20. In a coking retort oven, in combination: a plurality of coking chambers; heating walls intermediate such coking chambers and constituted of two series of vertical combustion flues alternately operable as upburning and as downburning flues and

- of a series of channels alternate units of which operate as exhaust channels for the upburning flues while the intermediate units operate as air channels for supplying pre-heated air to the downburning flues; means for feeding fuel gas to the flues when the flow is in either direction; means for permitting waste gas to flow from the upburning flues into the downburning flues; means 5 for periodically reversing the direction of flow in the flues and channels; and a periodically-reversible regenerative system for receiving the exhaust from all the flues and exhaust channels, combined with supply connections for conveying preheated air from such system to all the upflow flues and air channels; substantially as specified.
- 10 21. In a coking retort oven, in combina-

tion: a plurality of coking chambers; heating walls intermediate such coking chambers and constituted of series of combustion flues and of a series of channels intermediate such flue-series; cross-regenerators disposed at a lower level than the coking chambers and heating walls, such regenerators being 20 sub-divided into compartments with a compartment of each regenerator directly communicating with combustion flues and another compartment thereof directly communicating with intermediate channels of the heating walls; and means for permitting 25 separate control of the flow in each compartment of the regenerators; substantially as specified.

JOSEPH VAN ACKEREN.
